CONTOURED ARM BOARD FOR MEDICAL THERAPY

Lewis F. Hazlewood, 33 Perennial Lane, Willingboro, N.J., and Ronald J. Shea, 942 Mystic Lane, Norristown, Pa.

Filed Apr. 15, 1964, Ser. No. 79,500

Term of patent 14 years

(Cl. D83—1)

FIG. 1. FIG. 2. FIG. 3.

FIGURE 1 is a plan view of an arm board for medical therapy embodying our new design;

FIGURE 2 is a left side view thereof;

FIGURE 3 is a bottom view thereof;

FIGURE 4 is a front end view thereof; and

FIGURE 5 is a rear end view thereof.

We claim:

The ornamental design for a contoured arm board for medical therapy, as shown.

FIG. 4.

FIG. 5.
